C. C. FETTY ET AL.

PUMPING ATTACHMENT FOR OIL WELL RIGS

Filed Oct. 17, 1923

UNITED STATES PATENT OFFICE.

CHARLIE CAMDON FETTY AND GUSTAVIS LE ROY RAMSEY, OF ELDORADO, KANSAS.

PUMPING ATTACHMENT FOR OIL-WELL RIGS.

Application filed October 17, 1923. Serial No. 669,152.

To all whom it may concern:

Be it known that we, CHARLIE CAMDON FETTY and GUSTAVIS LE ROY RAMSEY, citizens of the United States, residing at Eldorado, in the county of Butler and State of Kansas, have invented certain new and useful Improvements in Pumping Attachments for Oil-Well Rigs; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a pumping attachment for oil well rigs and the primary object thereof is to provide a mechanism whereby the maximum stroke of the pump piston may be obtained, this being important in those wells which develop water and where it is desired to pump the water from the well. Prior to our invention it has been standard practice to leave the band wheel and the walking beam at the well at the completion of the drilling operation and to connect the pump rod to the walking beam so that when the band wheel is driven by an engine, the pump rod will be actuated. The objection to this practice is that in a drilling operation the movement of the drill rod in either direction is relatively slight whereas in a pumping operation a long stroke is desirable, consequently where the walking beam and band wheel of the drilling rig were made to impart motion to the pump rod, the movement of the piston was too slight to be really effective.

We have provided means whereby the band wheel and walking beam can still be used for the pumping operation but the connecting links between the band wheel and walking beam have been modified or changed to provide for a greater stroke than is normal to the drilling rig and also to provide an increase of power over the standard form of mechanism.

The novel features of the invention will be apparent by reference to the following description in connection with the accompanying drawings, in which—

Fig. 1 is an elevational view of a pumping rig constructed in accordance with our invention.

Fig. 2 is an enlarged horizontal, sectional view through the planetary gearing and the pitman which translates the rotary motion of the band wheel into the vibratory movement of the walking beam.

Fig. 3 is a vertical, sectional view on the line 3—3 of Fig. 2, and

Fig. 4 is a perspective view of the planetary gear.

Referring now to the drawings by numerals of reference:

1 designates the derrick platform upon which the standard 2 for the walking beam 3 is mounted. 4 designates the band wheel, 5 its shaft, 6 the jack post, and 7 the mud sills; these being parts of the normal drilling rig. In order to impart the greater throw to the walking beam we mount a gear 8 upon the axle of the band wheel. The gear 8 comprises a hub 9 having spaced flanges or disks 10 and 10' which have teeth 11 and 11' meshing with teeth 12 and 12' of a similarly constructed planetary gear 13 to which the pitman 14 is secured. The planetary gear is provided with two parallel flanges 15 and 16 between which is fastened the pitman 14.

The gears 8 and 13 are connected together by the cross head consisting of the two bars 23 and 24 fastened by the cross head members 25 and 26, the cross head members having notches to receive the hubs 9 and 17 respectively of the gears 8 and 13; the cross head being adjustable on the rods 23 and 24 by the nuts 27 and 28.

When the nuts 23 and 24 are taken off the rods or bars 23 and 24, the cross head or yoke can be removed to allow the gear 13 to drop so as to swing the front end of the walking beam 3 upward through a greater arc than is normally possible. Therefore, the front end of the walking beam can swing out of line with the pump rods to allow them to be "pulled."

The teeth 10 and 10' on the gear 8 and the teeth 12 and 12' on the gear 13 are shrouded to their pitch line as at 30 and 31 to form rolling surfaces 32 and 33 for the gears so that as the gear 13 planetates around the gear 8, the teeth will be kept in proper meshing relation which eliminates uneven stress upon the teeth which would tend to break them off or cause the gears to bind.

The pitman is connected to the walking

beam 3 by the stirrup 34 and the walking beam operates the pump rod 35 in an obvious manner.

When the parts are assembled and the band wheel is rotated, motion will be imparted to the pinion gear 8 which meshes with the gear 13, causing it to revolve about the axis of the gear 8. In other words, the gear 13 is a planetating gear induced to planetate by the bars 23 and 24 and by the cross heads 25 and 26. Since the gear 13 is a relatively larger gear as compared to pinion 8 it is apparent that as it planetates about the gear 8, a relatively long throw will be imparted to the walking beam 3 by which a corresponding long movement will be imparted to the pump rod and through it to the pump piston; therefore, the stroke of the piston will be much greater and with increase of power than it would be if the pump rod were operated solely by the conventional form of crank and band wheel.

It is to be understood, of course, that the shaft 5 can be conveniently mounted in the jack post box 36 although any other form of bearing may be employed.

What we claim and desire to secure by Letters Patent is:

1. In combination a pair of circular gears each gear having shrouds, and readily detachable means connecting the gears to normally maintain the shrouds in rolling contact and to permit separation of the gears, one of the gears being mounted upon a fixed axis, the other gear moving about the axis of the first in a circular path.

2. In a power transmission mechanism, a drive shaft, a circular gear rigid on the shaft, a walking beam, a pitman loosely connected to the walking beam, a second circular gear rigid on the pitman, shrouds on both gears and readily detachable means for normally maintaining the shrouds of the two gears in rolling contact, the removable means permitting the second gear to be moved away from the first to allow the front end of the walking beam to swing upwardly through a greater arc than that which it

can swing when the two gears are in mesh.

3. In combination, a pair of gears, each gear comprising a hub with two parallel webs to provide a space between the webs, each gear having a shroud extending to the pitch line of the teeth, means engaging the hubs between the webs connecting the gears together so that the shrouds of the respective gears will contact, one of the gears being mounted on a fixed axis, the axis of the other gear moving about the axis of the first in a circular path.

4. In a power transmission mechanism, a drive shaft, a circular gear rigid upon the drive shaft, a circular driven gear meshing with the first mentioned gear, outstanding flanges on the driven gear to receive a pitman between them, shrouds on the gears, and readily detachable means connecting the gears to normally maintain the shrouds in rolling contact and to permit separation of the gears, the second gear moving about the axis of the first in a circular path.

5. In combination, a pair of circular gears each having shrouds, one of the gears rotating about a fixed axis, the other gear moving about the axis of the first in a circular path, and readily detachable means connecting the gears to normally maintain the shrouds in rolling contact, said means comprising cross head members on the hubs of the respective gears and means for adjustably connecting the cross head members in cooperative relation.

6. In combination a pair of meshing circular gears each having shrouds, one of the gears rotating about a fixed axis, the other gear rotating about the first, and adjustable means connecting the hubs of the respective gears, said means comprising cross head members engaging the gear hubs, rods passing through one of the cross head members and nuts adjustably engaging the ends of the rods.

In testimony whereof we affix our signatures.

CHARLIE CAMDON FETTY.
GUSTAVIS LE ROY RAMSEY.
